UNITED STATES PATENT OFFICE.

HUBERT HIGGINS, OF CAMBRIDGE, ENGLAND.

APPARATUS FOR IMPREGNATING AND SEASONING WOOD.

SPECIFICATION forming part of Letters Patent No. 695,152, dated March 11, 1902.

Application filed November 13, 1901. Serial No. 82,141. (No model.)

To all whom it may concern:

Be it known that I, HUBERT HIGGINS, a subject of the King of Great Britain, residing at Cambridge, England, have invented certain new and useful Improvements in or Relating to Apparatus for Drying, Seasoning, and Impregnating Wood and other Substances, (for which I have made application for Letters Patent in Great Britain under No. 10,124, dated May 15, 1901,) of which the following is a specification.

This invention relates to improvements in apparatus for treating organic or inorganic substances with superheated steam and impregnating them with a preservative or other solution, the primary object of the invention being to provide economical and efficient apparatus for seasoning or seasoning and impregnating wood on a large scale.

In carrying out the invention I provide a chamber divided into compartments, preferably three in number, separated from each other by sliding doors adapted to be opened and shut from outside the chamber. Beneath one end of the chamber I provide a furnace, from which the products of combustion are caused to circulate around the chamber, the whole or greater part of its walls being made double with a space between them which acts as the flue for the furnace, baffle-partitions or the like being provided to circulate the gases as desired around the chamber before their escape by the chimney. I may provide extra furnaces under the other sections of the chamber for, first, regulating the temperature of the same; second, preventing undue condensation. The furnace is provided with a steam-superheater, preferably comprising a cast-iron box forming part of the front or side of the furnace. It may be provided with a removable cover and is connected with any convenient supply of steam. The inner wall of the box forms a tube-plate, into which are fixed (preferably by means of back-nuts) a series of steam-pipes, which are carried through the upper part of the furnace below the chamber-floor and thence pass directly into that end compartment of the chamber beneath which the furnace is placed or into a collecting box or tube arranged over the furnace-bridge, one or more main delivery-pipes being carried from this box into the compartment,

these mains being fitted with distributing-pipes as desired. The distributing-pipes may be perforated or preferably have open ends, 55 which are placed adjacent and opposed to the walls of the chamber, so as to diffuse the steam escaping therefrom equally throughout the same. Means may be provided to protect the superheated pipes at will from the direct action of the fire—say a plate sliding in guides, so as to be placed when desired under the steam-pipes. The other compartments of the chamber may be provided with a similar system of distributing-pipes; but these start for 65 each compartment from a pipe passing through the side walls of the chamber and ending outside, with one-half of a coupling placed within or adjacent to a manhole formed in the side of the adjacent compartment for a 70 purpose hereinafter described. The floor of the chamber is provided with rails, so that trucks or tanks can be drawn from one compartment to another.

The material to be treated is stacked in 75 tanks carried on wheels and open at the top, so that the steam can circulate throughout the mass. Leading from the bottom of each tank are one or more pipes ending in a common flexible pipe, on the free end of which is 80 a half-coupling corresponding to the half-couplings already above described. The tanks are so proportioned that when within a compartment of the chamber this flexible pipe can be readily reached by a hook or the 85 like and manipulated from the outside of the chamber, so as to be pulled through the compartment-manhole and coupled onto the distributing-main of the next compartment. The tanks may be provided with a perforated 90 false bottom, the pipes leading from the space thus formed so as to equalize the distribution of the current of steam passing through the material and escaping by the pipes. The tanks are provided with couplings which can 95 be coupled and uncoupled by means of a pole or the like operating through the manhole—say a pivoted hook on one end of a tank normally held by springs in a vertical position, but which on being released engages an eye 100 on the end of an adjacent tank. When in continuous work, a tank is located in each compartment, the tank in the end compartment, under which the furnace is placed, has

- its flexible pipe connected with the adjacent compartment, the tank in the latter compartment with the next compartment, and so on, the steam from the tank in the last compartment escaping into the chimney or otherwise. Steam is admitted into the superheater and passes thence into the compartment over the furnace, which is the last compartment in the process of treatment; the material being subjected in this compartment to the highest temperature. The superheated steam circulates downward through the material in the tank and then passes through the flexible pipe into the next compartment. From this compartment it passes in a similar manner through the material in the tank into the next compartment. Usually three compartments only are employed, and from the third compartment the gases are allowed to escape into the atmosphere, or they may be utilized for other heating or drying purposes. After the material has been treated for a sufficient length of time the supply of steam is cut off. The tank in the last or hottest compartment is now filled with the impregnating solution, a pipe with requisite connections leading into the chamber being provided for this purpose. The flexible pipes are now uncoupled, the doors between the compartments raised, and the tanks coupled together. The doors leading into the end chambers are opened and a tank with fresh material to be treated coupled onto the tank in the compartment lowest in temperature and an engine or some form of tractive power attached to the tank which has been treated with the solution, or the power which has been used to bring the tank of fresh material up to the chamber may be employed to push the tanks forward. The train of tanks is drawn forward till the impregnated tank is free of the chamber and the tank of new material within the chamber, when the tanks are uncoupled, the doors closed, and the process repeated.
- The temperature of the various compartments will vary according to the kind of material treated and especially the size in cross-section of the individual pieces of that material.
- Means may be provided for passing only a portion of the superheated steam from one chamber into the next and for regulating the action of the flues, so as to control the temperature of the compartments.
- Convenient means are provided for opening and closing the doors and for bringing the tanks up to and removing them from the vicinity of the chamber. Pyrometers and other fittings are provided and means for withdrawing the residue of the impregnating solution from the tanks on the completion of the process.
- The chamber may be employed for drying purposes or for seasoning wood without impregnating it.

An endless chain might be arranged for giv-

ing travel to the tanks, in which case end couplings would not be required.

In the accompanying drawings, Figure 1 is a central longitudinal vertical section showing a convenient form of apparatus for carrying out my invention. Fig. 2 is a horizontal section on the line 2 2 of Fig. 1. Fig. 3 is a vertical cross-section on the line 3 3 of Fig. 1; and Fig. 4 is a vertical longitudinal section of an end compartment, showing the arrangement of the steam-distributing pipes.

Like letters indicate like parts in all figures.

A is a chamber, preferably constructed of brick, provided with doors A⁴ A⁵, one at each end, and divided by doors A⁶ A⁷ into three compartments A' A² A³. The chamber is constructed with double walls, forming a flue A⁸ for a superheating-furnace B, provided beneath the compartment A³. Conveniently the flue A⁸ is arranged so that the furnace-gases pass successively around each compartment, finally escaping from the flue—say at A⁹—into a shaft. (Not shown.)

The superheater comprises a number of pipes or tubes C', arranged at a convenient height above the furnace-grate B', so that the combustion-gases pass around them on their way to the flue A⁸. The tubes C' are fixed at one end into a cast-iron box C, placed in one of the side walls of the furnace, their other ends being connected to a large tube or box C², built in the inner wall of the chamber over the furnace-bridge. Conveniently the tubes are secured in the boxes C C² by means of back-nuts, allowing of their ready removal for repair. From the box C² run one or more distributing-mains C³, from which distributing-pipes C⁴ are arranged over the sides of the compartments A³, these latter pipes having open ends C⁵ directed against the walls of the chamber to diffuse the escaping steam. The steam is supplied to the box C through a pipe C⁶ and may be derived from any convenient source. Waste or exhaust steam may be employed, if such be available. Beneath the tubes C' is a sliding plate B², capable of being controlled by the stoker from the outside of the furnace, so as to cut off a part or all of the tubes from the direct action of the furnace. A side connection between the furnace and the flue A⁸, normally closed by a damper B³, may be provided to divert, if desired, a portion or the whole of the combustion-gases from the superheating-tubes.

The doors A⁴ A⁵ A⁶ A⁷ are arranged to run in guideways provided in or on the side walls of the chamber and through slots left in the top wall. A convenient arrangement for readily raising and lowering them is illustrated in Figs. 3 and 4, the doors being hung on chains or ropes D, arranged to wind around pulleys D', carried on a revoluble shaft D². This shaft may be revolved by hand by means of the sprocket-wheels D³ D⁴ and chain D⁵. The doors are counterbalanced by weights D⁶.

The floor of the chamber is provided with

rails A¹⁰, extending beyond the chamber and on which stand wheeled trucks E, open at the top and of a size to approximately fill one compartment. Each truck is formed with a 5 perforated false bottom E', forming a space E², which is continued up one end of the truck, preferably in a triangular shape, as shown in Fig. 3, and ends in a flexible pipe E³, on the free end of which is a half-coupling. The space E² is gradually diminished 10 in width, as shown, so as to equalize the flow of the steam through the timber or other material stacked in the truck, for which purpose the perforations in the false bottom may 15 also advantageously be made smaller toward the exit end of the space E². The timber F⁴ or other material is stacked, as shown in the figures, with passages between the pieces, so as to allow of a free passage for the steam. 20 At the side of each compartment is an opening F through the double wall, provided with a door F'. These openings are so placed that when the trucks are in position within the compartments the flexible pipes E³ can be 25 easily reached from the outside and drawn out—say by a hook or the like—so that the half-coupling on their ends can be coupled to corresponding parts of couplings fixed on the end of a pipe F², Fig. 2, which forms a communication between the opening and the adjacent compartment. This pipe may be controlled by a valve or cock F³. The pipe F² in the compartment A' opens into the atmosphere, forming the escape-pipe into the atmosphere for the used superheated steam and the moisture or other gases driven off from the material. The trucks are provided with 30 couplings G G', which may be of any convenient construction so arranged that they 35 can be uncoupled and coupled from the outside by means of a coupling-pole passed through the openings F. Each truck is provided with an escape-valve or stop-cock E⁴ to remove the liquid at the end of the operation 40 when an impregnating process is being carried out. The compartment A³ is furnished 45 with an inlet-pipe H through its roof, placed centrally over the truck in position in that compartment, this pipe being connected with 50 the supply of impregnating fluid placed in any convenient position. It is conveniently provided with a valve H'.

The operation of the apparatus is as follows: The timber F⁴ or other material is 55 stacked in the tanks so as to allow the steam to pass freely around it—say as shown in Figs. 1 and 2. A truck is placed in each compartment and the doors closed, and the pipe E³ of the tank in each compartment A³ A² A' 60 is coupled to its respective pipe F², communicating with the following compartment or with the atmosphere. Steam (which may be waste steam) is admitted into the box C and passes into the chamber A³ through the superheating-pipes C', tube C², and pipes C³, being 65 superheated on its way through the furnace B, the combustion-gases of the latter being

circulated around each compartment successively through the flues A⁸, finally escaping to the chimney through the exit-flue A⁹. 70 The amount of superheating given to the steam may be regulated by means of the sliding plate B³ cutting off at will a portion or all of the superheating-pipes from the direct action of the furnace. A part or the whole 75 of the furnace-gases may be diverted directly into the flue A⁸ by means of the damper B³. The steam diffused throughout the compartment A³ from the pipes C⁴ passes down through the material in the tank and through 80 the perforations in the false bottom into the space E² and through the pipes E³ F² into the compartment A². From this compartment the gases pass in a similar manner to the compartment A' and thence escape into the atmosphere. When the material in the compartment A³ has been sufficiently treated, the supply of steam is shut off, and if it be desired to impregnate the material the valve 85 H' is opened and the tank filled with the impregnating fluid. The doors are then opened, the pipes E³ uncoupled, the couplings G' 90 coupled, and the tanks pulled forward the distance of one compartment. The tank from the compartment A³ is then removed, a fresh 95 tank placed in the compartment A', the doors closed, and the operation repeated.

What I claim as my invention, and desire to secure by Letters Patent, is—

1. The combination with a drying-chamber divided into a series of compartments with adjustable means of communication between each compartment means for passing a fluid into the first compartment, an opening for the exhaust of the same from the last compartment of the series, and openings forming a passage for the fluid between adjacent compartments, of a series of open tanks adapted to be placed in and removed from each compartment and devices for connecting and disconnecting the bottom of each tank when in a compartment with one of the said communicating openings or with the exhaust-opening substantially as described. 100

2. The combination with a drying-chamber divided into a series of compartments, adjustable means of communication between each compartment, a furnace of which the flue forms a jacket to the chamber, a superheater placed in said furnace and connected 105 with a source of steam and one end compartment of the chamber respectively and an exhaust-opening in the other end compartment, of a series of open tanks and means to connect the bottom of a tank when within a compartment with the interior of an adjacent compartment or with the exhaust-opening so as 110 to pass the superheated steam successively through all the tanks and compartments substantially as specified. 115

3. The combination with a drying-chamber having a series of compartments, sliding doors between adjacent compartments, a pipe or pipes for introducing a hot fluid into one end 120

compartment of the series and a communication $F F' F^2$ between adjacent compartments and between one end compartment and the atmosphere, of a series of open tanks each tank having a perforated false bottom and means such as a flexible pipe for connecting the space thus formed with one of the aforesaid communications $F F' F^2$ substantially as described.

- 10 4. The combination with a drying-chamber having a series of compartments, sliding doors between adjacent compartments, a furnace beneath one end of the chamber the flue of which forms the jacket to said chamber, a superheater within said furnace communicating respectively with a source of steam and with the interior of one end compartment of the chamber, and a communication $F F' F^2$ between adjacent compartments and between the other end compartment and the atmosphere and a series of open tanks, each tank having a perforated false bottom, a flexible pipe for connecting the space thus formed in the bottom of each truck with one of the aforesaid communications $F F' F^2$ and a valve-controlled outlet from such space and a valve-controlled inlet-pipe communicating respectively with a supply of impregnating material and with the end compartment with which the superheater is connected, substantially as described.
- 15 5. The combination with a drying-chamber having a series of compartments, sliding doors between adjacent compartments and between the other end compartment and the atmosphere and a series of open tanks, each tank having a perforated false bottom and means such as a flexible pipe for connecting the space thus formed in the bottom of each truck with one of the aforesaid communications $F F' F^2$ substantially as described.
- 20 6. The combination with a drying-chamber having a series of compartments, sliding doors between adjacent compartments and between the other end compartment and the atmosphere and a series of open tanks, each tank having a perforated false bottom and means such as a flexible pipe for connecting the space thus formed in the bottom of each truck with one of the aforesaid communications $F F' F^2$ substantially as described.
- 25 7. The combination with a drying-chamber having a series of compartments, sliding doors

between adjacent compartments, a furnace beneath one end of the chamber the flue of which forms the jacket to said chamber, a superheater within said furnace communicating respectively with a source of steam and with the interior of one end compartment of the chamber, and a communication $F F' F^2$ between adjacent compartments and between the other end compartment and the atmosphere and a series of open tanks, each tank having a perforated false bottom, a flexible pipe for connecting the space thus formed in the bottom of each truck with one of the aforesaid communications $F F' F^2$ and a valve-controlled outlet from such space and a valve-controlled inlet-pipe communicating respectively with a supply of impregnating material and with the end compartment with which the superheater is connected, substantially as described.

In testimony whereof I have signed my name to this specification in the presence of two subscribing witnesses.

HUBERT HIGGINS.
